COMBINED VIBRATOR AND VACUUM APPARATUS.

1,025,504.

Specification of Letters Patent.

Patented May 7, 1912.

Application filed July 31, 1911. Serial No. 641,647.

To all whom it may concern:

Be it known that we, JAMES BIRRELL and WILLIAM BIRRELL, citizens of the United States, residing at Seattle, in the county of 5 King and State of Washington, have invented certain new and useful Improvements in Combined Vibrators and Vacuum Apparatus, of which the following is a specification.

10 This invention relates to vibrators for the treatment of certain forms of disease and to vacuum inductors of the same class.

The object of the invention is to combine these beneficial agencies for the treatment of 15 abnormal conditions that their healing functions may be utilized simultaneously, separately or alternately.

Further objects of the invention will be apparent from the following description of 20 the invention and its application.

The invention consists in the novel construction and combination of a fluid-actuated vibrator and a fluid-jet induced vacuum apparatus, together with the adaptation of 25 parts therewith, as will be hereinafter described in the following specification, illustrated in the accompanying views, and finally set forth in the appended claims.

In said views Figure 1 is a view of an 30 embodiment of the invention shown partly in side elevation and partly in vertical section with a portion of the flexible shafting broken away. Fig. 2 is a vertical sectional view of the actuating mechanism. Fig. 3 is a cross-sectional view on the lines 3—3 of 35 Fig. 1. Fig. 4 is a sectional view of an attachment of the invention.

Referring to said drawings, the reference 40 numeral 1 designates a tubular casing provided at one of its ends with an internally threaded socket 2 which may be screwed directly upon the threaded bib of a water-faucet or, as shown, similarly connected with an attachment 3 for making a water-tight 45 joint with a faucet unprovided with screw-threads. The opposite end of said casing is enlarged to afford a tangentially arranged bulbous extremity having an interior spheroidal chamber 4 provided with a consider- 50 able number of outlet holes 5 in its bottom wall. Numerals 6 and 7 designate concavo-convex partitions across the upper and lower ends, respectively, of the tubular portion of

said casing to afford a suction-chamber 8 therebetween. Axially arranged apertures 55 6' and 7' are provided in the respective partitions in vertical alinement with the axis of the faucet receiving attachment 3, the latter of which apertures is of larger diameter than the upper one. The numeral 10 denotes a tubular extension preferably radial to said bulb and rectangular to said tubular casing 1. It is provided with a nipple 11 at its outer extremity and its inner end is closed from communication with said chamber 4 by an axially alined plug 12. The bore 13 of said extension is provided with a side-issuing outlet through a pipe 14 communicating with the upper portion of the suction-chamber 8. 15 indicates a rotatable shaft 60 65 mounted axially of said extension 10 in bearings in plug 12 and in the opposite wall of said casing at 16. Operatively connected with said shaft is a jet power wheel 17 having buckets 18 at spaced intervals about its 70 periphery. 19 is a disk fixedly mounted for rotation with said wheel and adapted to be impinged by a clamping screw 20 entered through a threaded hole in the casing to prevent at times the rotation of the wheel. 75 80

The outer end of the shaft 15 is extended into the bore 13 and there connected with an end of a flexible shaft 21 by a coupling 22. Said flexible shaft may be and is preferably of considerable length and at its remote extremity is connected, as by a coupling 22', to a short length of rigid shafting 23 rotatably mounted in a vibrator head. Said head consists in a globular casing 24 having an interior chamber divided by a wall 25 into 90 inner and outer compartments 26 and 27. 28 is a radially arranged tubular extension to said head integrally or otherwise connected at its inner end centrally of said wall 25. An axial bore 29 is provided in said extension 28 for the reception of an end of the flexible shaft 21 and its connecting rigid shaft 23, as before explained. The latter is extended through a bearing in the wall 25 and its end protruding into the outer compartment 27 is provided with an arm 30 fixedly secured thereto in proximity of one of its ends and adapted to be revolved with the shaft 23 in a plane parallel with the wall 25. Said flexible shaft 21 is comprised of a 100 105 length of relatively small closely coiled spring

wire. Surrounding said shaft with an annular space 31 therebetween is a flexible coiled wire sheath 32 fixedly secured at each of its ends to the interior surface of the respective tubular extensions 10 and 28. 33 denotes a section of rubber, or other yielding air-tight tubing incasing said metal elements of the shaft. It is engaged over the nipple 11 and the like part 34 of the extension 28 and affords air-tight communication from the bore 13 to the bore 29 of the vibrator. Apertures 35 and 36 respectively connect the last named bore with the inner compartment 26 and the latter with the compartment 27. Access from compartment 27 to the atmosphere is had through an outwardly protruding tubular nipple 37 adapted to receive an apertured applicator attachment 38 (see also Fig. 4). Said compartment 27 is provided with a threaded vent-hole to receive a bifurcated screw 39 for regulative communication with the atmosphere.

40 denotes a cushion handle grip overlying the tubular extension 28 through which 25 a secure grasp of the vibrator may be had and the latter conveniently manipulated.

The operation of the invention may be described as follows: The apparatus is adapted to be attached to a water-faucet either 30 through the employment of the attachment 3 or coupled directly therewith through the internally threaded socket 2. Said faucet is connected to a source of water-supply under pressure. Upon the water being turned on 35 it flows with high velocity through the aperture 6' of the partition 6 into the suction chamber 8 and thence through the aperture 7' where it impinges upon the blades of the water-wheel 17 to cause the same to revolve 40 and is discharged through the outlet holes 5. The rotary motion of the wheel is transmitted through the shafts 15, 21 and 23 to the vibrator-head. The arm 30 fixed to an end of the shaft 23, is rotated at a high velocity and owing to its unbalanced connection with its rotating shaft creates a series of rapid vibratory waves which are communicated through the vibrator-head to the applicator. As the water is forced through the 45 aperture into the suction-chamber 8 and from thence through the aperture 7' it creates a partial vacuum within said chamber inducing a flow of air into the suction chamber through the pipe 14 connecting with the 50 bore 13. The influence of said suction is communicated through the annular space 31 within the tubing 33 to the bore 29 whence air is drawn through the apertures 35 and 36 to the tubular nipple 37 where access to 55 atmospheric air is had axially of the suitable applicator attachment. It will be seen that the vibrations due to the rotary movements of the water-wheel and attachments, and the suction communicated to the tubular nipple

simultaneous and may be applied at the combined so-called vibrator and suction head to many useful and beneficial results, both in unison and separately. Said applicators may be made in wide variety of forms to accomplish the various functions of which the apparatus is capable. The form shown in section in Fig. 1 attached to the head is of a style favored for treating the scalp. The projections 41 when vibrated and brought 70 into contact with the scalp apply a mild beneficial massage to the skin at the same time loosening any scale or dandruff that may be present while the suction of air through the nipple 37 draws any dust or 80 scale therethrough and carries the same into the suction-chamber 8 where it is mingled with the water and discharged through the holes 5.

In Fig. 4 is shown a form of applicator 85 through which the vibrations may be communicated to the surface of the body and coincidentally apply a partial vacuum thereto. The device comprises flexible rubber annular walls 42 inclosing a cup-like depression 43. The aperture 44 is adapted to fit over the nipple 37 and when the outer perimeter 45 of said walls is brought into contact with the surface of the body, the air is rarefied in said depression by the aforesaid 90 suction. The concurrent vibrations do not cause the partial vacuum to be impaired to any extent but facilitate the movement of the device along the surface of the skin. This method of treatment combines the exhilaration and stimulation accompanying the mild application of the vibrations with the local removal of air pressure from the part inducing a mild congestion of blood or 95 hyperemia thereat with marked curative effects in some cases. The amount of air suction may be regulated independently of the velocity of the water jet and the speed of the water wheel by the provision of the bifurcated screw 39. The latter may be inserted 100 its entire length into the vent to completely close the same which will cause the entire pressure of the suction to be felt at the applicator. The screw 39 may be withdrawn, however, to uncover a more or less 105 amount of the slot therein which will relieve said pressure at the applicator to a corresponding degree. No appreciable suction or vacuum would be felt at the applicator when the said screw is withdrawn to its 110 maximum extent in order to afford opportunity for the vibratory functions of the apparatus to be applied independently of the suctional effects. Likewise the rotary motion of the wheel may be stopped by the 115 manipulation of the screw 20 to cause it to bear upon the disk 19 with sufficient force 120 to maintain said wheel at rest. Thus it will be seen that the two primary functions of 125

or each separately and some of the most marked curative effects of treatment available with the apparatus are obtained through alternating said methods of treatment by relatively short intervals.

5 The apparatus is especially adapted to use by practitioners of medicine and barbers. In its use by the latter the feature of removing from the hair of the person being 10 treated all dust and germs as soon as loosened from its habitat and preventing same from being set free in the atmosphere has been recognized as a valuable one and one not heretofore available for such purpose.

15 While we have described the illustrated embodiment of our invention with some particularity we do not intend to be understood as confining ourselves to the precise form shown as various changes in detail and

20 modification of design may obviously be made within the spirit of the invention, and within the scope of the appended claims.

What we claim as our invention, is—

1. In apparatus of the class described, 25 fluid induced suction device, a motor operated by fluid discharged from said suction device, and means including suitable connections for applying suction and vibrations caused by said device and motor.

30 2. In apparatus of the class described, fluid actuated means for creating a vacuum, power devices actuated simultaneously by said fluid, apparatus in common whereby said vacuum is applied, and power from 35 said devices is utilized in the form of vibrations, and flexible operative connections between said apparatus and said means and devices.

3. In apparatus of the class described, a 40 fluid induced suction device, a motor operated by fluid discharged from said suction device, means including suitable connections for applying suction and vibrations caused by said device and motor, and means to vary 45 the amount of suction.

4. In apparatus of the class described, a 50 vibrator, including a suction applicator, fluid actuated power mechanism, fluid operated suction inducing apparatus associated therewith, and operative connections between said mechanism and said vibrator including air-tight communication between 55 said suction devices.

5. In apparatus of the class described, 60 fluid induced suction device, a motor operated by fluid discharged from said suction device, means including suitable connections for applying suction and vibrations caused by said device and motor, and means to cause said motor to be inoperative.

6. In apparatus of the class described, a 65 fluid induced suction device, a motor operated by fluid discharged from said suction device, means including suitable connections for applying suction and vibrations caused

75 by said device and motor, means to vary the amount of suction, and means to cause said motor to be inoperative.

7. In apparatus of the class described, the combination of a fluid actuated motor, 70 and fluid induced suction device, a device for converting rotary motion of said motor into vibratory waves in common with devices for conveying and applying said suction.

75 8. In apparatus of the class described, a casing including a suction chamber and a power chamber provided with means for attachment to a water-faucet, a motor in said power-chamber, a vibrator head, flexible connections between the casing and said head conveying in common rotary motion from said motor and suction from said suction chamber.

80 9. In apparatus of the class described, a tubular casing provided at one end with means for attachment to a water-faucet and at its opposite end with a power chamber having discharge openings therein, apertured partitions in said casing spaced apart 90 to afford a suction chamber therebetween, a fluid actuated motor in said power chamber, a vibrator head, flexible connections between said motor and said head, means in said head to convert rotary motion of said motor into 95 vibrations, an applicator attachment to apply said vibrations to a surface, and a passageway between said suction chamber and said attachment.

10. In apparatus of the class described, a 100 casing provided with means for attachment to a source of water supply under pressure at one end; a power chamber provided with a discharge outlet at its other end, and an intermediate suction chamber, a fluid power 105 motor in said power chamber, a vibrator head, an applicator attachment mounted on said head, said head and applicator having a continuous passage therethrough, a flexible shaft rotatively connected to said motor and 110 terminating within said head in an unbalanced arm, a covering for said shaft affording a continuous air-tight duct therethrough, and connections between said duct and the suction chamber.

11. In apparatus of the class described, a 115 casing provided with a means for attachment to a source of water supply under pressure at one end, a power chamber provided with a discharge outlet at its other end, and an intermediate suction chamber, a fluid power motor in said power chamber, a brake upon said motor, a vibrator head, an applicator attachment mounted on said head, said head and applicator having a continuous 120 passage therethrough, supplementary means to admit air within said passage, a flexible shaft rotatively connected to said motor and terminating within said head in an unbalanced arm, a covering for said shaft afford- 125

ing a continuous air-tight duct therethrough, and connections between said duct and the suction chamber.

12. In apparatus of the class described, a casing provided with means for attachment with a source of water supply, a suction chamber, and a power chamber having discharge openings therein, a fluid actuated motor in said power chamber, a vibrator head, flexible shaft connections between the motor and head, means connected to said shaft in the head to convert rotary motion into vibrations, an applicator detachably secured to said head, and a passageway between said applicator through the head and shaft to said suction chamber.

13. In apparatus of the class described, a casing provided with means for attachment with a source of water supply, a suction chamber, and a power chamber having discharge openings therein, a fluid actuated motor in said power chamber, a brake upon said motor, a vibrator head, flexible shaft connections between the motor and head, means connected to said shaft in the head to convert rotary motion into vibrations, an applicator detachably secured to said head, and a passageway between said applicator through the head and shaft to said suction chamber.

14. In apparatus of the class described, a casing provided with means for attachment

with a source of water supply, a suction chamber, and a power chamber having discharge openings therein, a fluid actuated motor in said power chamber, a vibrator head, flexible shaft connections between the motor and head, means connected to said shaft in the head to convert rotary motion into vibrations, an applicator detachably secured to said head, a passageway between said applicator through the head and shaft to said suction chamber, and means to admit air into said passageway.

15. In apparatus of the class described, a casing provided with means for attachment with a source of water supply, a suction chamber, and a power chamber having discharge openings therein, a fluid actuated motor in said power chamber, a brake upon said motor, a vibrator head, flexible shaft connections between the motor and head, means connected to said shaft in the head to convert rotary motion into vibrations, an applicator detachably secured to said head, a passageway between said applicator through the head and shaft to said suction chamber, and means to admit air into said passageway.
